UNITED STATES PATENT OFFICE.

HENRIETTA C. SHAW, OF KANSAS CITY, MISSOURI.

DESIGN FOR A PIN AND RING BLANK.

SPECIFICATION forming part of Design No. 30,994, dated June 13, 1899.

Application filed March 30, 1899. Serial No. 711,165. Term of patent 14 years.

To all whom it may concern:

Be it known that I, HENRIETTA C. SHAW, a citizen of the United States, residing at Kansas City, in the county of Jackson and State of Missouri, have invented and produced a new and original Design for Pin and Ring Blanks, of which the following is a specification.

My invention relates to a new and useful 10 design for a pin and ring blank.

In the accompanying drawings, Figure 1 represents a plan view, Fig. 2 an edge view, and Fig. 3 a central cross-section, of a pin and ring blank, showing my new design, and 15 the leading or material feature of the same resides in a long narrow figure A, having its side margins extending for the greater part of its length in substantially parallel lines and tapered to a long narrow point B at one 20 end, and provided near one end with the narrow longitudinally-extending slot-like figure C and near its opposite end with the narrow longitudinal neck D, said neck occurring between two substantially rectangular figures 25 d d in the opposite margins of the figure.

Minor features of my design are embraced in the reduced width of the figure at a point between the said neck and the adjacent end of the blank, the side margins of this reduced

portion being curved, as at e e; also, in the reduced width of the figure adjacent to the slot-like figure C, from which point said reduced portion increases gradually in width in long sweeping curves f f; also, in the reduced width of the figure adjacent to the narrow neck D, 35 said reduced portion increasing gradually in width by the divergence of its margins g g h h from the opposite ends of said narrow neck; also, in the segmental formation as viewed in cross-section of the blank, as at i, 40 and its tapering or gradually-diminishing thickness from its middle or thickest point to said slot-like figure and neck, from the latter point of which its sides or faces are parallel, while from the former its sides or faces are 45 parallel for a slight distance and then diverge to a point K, from which point they taper to a long narrow point B.

What I claim is—

The design for a pin and ring blank, as 50 herein shown and described.

In testimony whereof I affix my signature in the presence of two witnesses.

HENRIETTA C. SHAW.

Witnesses:

M. R. REMLEY,
H. C. RODGERS.
